UNITED STATES PATENT OFFICE.

WILLIAM JARVIO, OF QUINCY, MASSACHUSETTS.

REFACING BUSHING TOOL.

Application filed May 5, 1924. Serial No. 711,268.

To all whom it may concern:

Be it known that I, WILLIAM JARVIO, a citizen of the United States, residing at Quincy, in the county of Norfolk and State 5 of Massachusetts, have invented certain new and useful Improvements in Refacing Bushing Tools, of which the following is a specification.

This invention relates to a tool for refacing bushings and the like and has for its 10 prime object to provide a device of this nature possessing a very simple and efficient construction, one which is reliable in operation, inexpensive to manufacture, and well 15 adapted to the purpose for which it is designed.

Another important object of the invention is to provide a device of this nature which is easily assembled and which may be readily 20 engaged or associated with the object upon which it is to operate.

With the above and numerous other objects in view as will be hereinafter more fully described and claimed, the invention resides 25 in certain novel features of construction, and in the combination and arrangement of parts as will appear as the description progresses.

In the drawing:

Figure 1 is an elevation of the tool embodying my invention showing a steering 30 knuckle of an automobile in section,

Figure 2 is a fragmentary elevation of the upper part of the tool, portions being shown in section and substantially on the line 2—2 35 of Figure 1,

Figure 3 is an elevation of the lower portion of the tool, and

Figure 4 is a perspective view of the blade.

Referring to the drawing in detail it will 40 be seen that 1 designates the elongated stem which terminates at its upper end in a threaded portion 2 which is bifurcated by a slot 3 extending from its end toward its intermediate portion. A blade 4 is in the form 45 of a U-shaped plate having its terminals 5 oppositely beveled so as to form cutting edges 6. This blade plate 4 is positioned in the slot 3 so as to extend transversely of the stem. A washer 7 is placed over the threaded portion 2 of the stem to rest on the blade 4 and a head or nut 8 provided with a threaded bore 9 is then screwed over the threaded portion 2 of the stem 1 so as to secure the blade in place. The rod 10 extends 50 through this head or nut 8 for turning the

stem and also for screwing the head or nut on the threaded portion of the stem. In using the device for refacing the bushings 12 of a steering knuckle 13 the stem is passed therethrough as is shown to advantage in 60 Figure 1 so that the cutting edges 6 of the blade 4 rests on one of the bushings 12. A sleeve 14 is placed on the end of the stem 1 opposite to the threaded portion 2 so as to engage the lower bushing 12 with its upper edge. The lower edge of this sleeve is in the form of two cams 15. A pin 16 is passed through the stem 1. A rod 17 forming a handle projects from the sleeve 14 in order that it may be rotated so that the cams 15 70 engage the pin 16 will force the blade 4 into engagement with the upper bushing 12. Now by turning the head 8 the blade will efficiently reface the bushing 12 shown at the top of the knuckle 13 and may be properly adjusted by further turning of sleeve 75 14. It is evident that in order to reface the bottom bushing 12 that the tool should be reversed.

This tool was designed particularly for 80 use in refacing the bushing of steering knuckles and the like but of course is capable of being efficiently used in other ways, the present example being sent forth merely to illustrate the utility of the device. It is 85 also evident that numerous changes in the details of construction, and in the combination and arrangement of parts may be resorted to without departing from the spirit or scope of the invention as hereinafter 90 claimed or sacrificing any of its advantages.

Having thus described my invention, what I claim as new is:

1. A tool of the class described including a stem, a blade rigidly mounted on one end 95 of the stem, a sleeve rotatably and slidably mounted on the other end of the stem and having its outer end in the form of a cam, a removable pin on the stem engaged with the cam of the sleeve, and means for facilitating manual rotation of the sleeve on the stem for adjusting the blade into engagement with the object to be refaced.

2. A tool of the class described including an elongated stem having a slotted and threaded end, a blade in the slotted and threaded end, a nut on the slotted and threaded end to hold the blade in place, a rod extending through the nut for screwing the same on the stem and also turning the stem 105 110

and the blade, and means on the stem for holding the blade in engagement with an object.

3. A tool of the class described including an elongated stem having a threaded and slotted end, a blade of U-shaped structure having its ends beveled to form cutting edges and situated in the slotted end of the stem, a nut threaded on the slotted end of the stem

holding the blade in place, a rod extended 10 through the nut for operation thereof and also for turning the stem, a sleeve on the stem a distance from the blade and having its end situated farther from the blade in the form of a cam, and a member on the stem to be 15 engaged by the cam.

In testimony whereof I affix my signature.
WILLIAM JARVIO.
